UNITED STATES PATENT OFFICE.

ABRAHAM B. LANDIS, OF WAYNESBORO, PENNSYLVANIA.

AUTOMATIC SIZING MECHANISM FOR GRINDING-MACHINES.

SPECIFICATION forming part of Letters Patent No. 781,434, dated January 31, 1905.

Application filed March 30, 1904. Serial No. 200,767.

To all whom it may concern:

Be it known that I, ABRAHAM B. LANDIS, a citizen of the United States, residing at Waynesboro, in the county of Franklin and State of Pennsylvania, have invented certain new and useful Improvements in Automatic Sizing Mechanism for Grinding-Machines, of which the following is a specification.

The object of my said invention is to provide an attachment for automatic feed mechanism for feeding the grinding-wheel of grinding-machines to the work of that general character shown in my former Letters Patents, Nos. 640,669 and 654,314, whereby the feed may continue until the exact size of the work desired has been reached and then be thrown out of operation. In the mechanism shown in said patents the wear of the grinding-wheel in reducing the work to the size required is compensated for by turning back by hand the trip which throws the feeding mechanism out of operation.

My present invention is for doing this work by an automatically-controlled electric motor, all as will be hereinafter more fully described and claimed.

Referring to the accompanying drawings, which are made a part hereof, and on which similar reference characters indicate similar parts, Figure 1 is a rear elevation of a grinding-machine embodying my said invention; Fig. 2, a cross-section through said machine; Fig. 3, a side elevation, on an enlarged scale, of the ratchet-wheel for actuating the feeding mechanism and the parts for operating said wheel automatically; Fig. 4, a side elevation, on an enlarged scale, of the size-determining device; Fig. 5, a section through the same looking in the direction indicated by the arrows from the dotted line 5 5 in Fig. 6; Fig. 6, a vertical section looking in the direction indicated by the arrows from the dotted line 6 6 in Fig. 5, and Fig. 7 a detail view showing the cam-wheel 16 in side and edge elevation.

In said drawings the portions marked A represent the bed of the machine; B, the carriage; C, the table; D, the slide, and E the grinding-wheel base. The frame A, carriage B, table C, slide D, and grinding-wheel base

E are all of a common and well-known construction, such as is shown in several of my former patents, and need, therefore, no particular description herein. The grinding-wheel E' is supported on the grinding-wheel base E in the usual manner and driven by an appropriate power. The work w is mounted in the head-stock and foot-stock C', supported on the table C, as usual.

The mechanism for feeding the wheel-base E to the work is of an analogous construction and arrangement to that shown in my other patents and is operated by a hand-wheel 1, mounted upon a shaft 2, journaled in suitable bearings in a bracket on standard 3 on the top of said wheel-base. Said shaft 2 is provided with a worm 70, which engages with a gear 71 on the top of a vertical shaft 72, which is connected by suitable gearing to move the base E back and forth upon the slide D. Ratchet-teeth are cut in the rim of wheel 1, as shown in Fig. 1 and at the left in Fig. 3, (a portion of ring 22 being broken away for this purpose,) which are adapted to be engaged by a pawl 5, mounted in a socket in the vertical arm of a bell-crank lever 6, which is mounted on a pivot 7 on the lower end of a bracket 8, attached to a part of standard 3 adjacent to said wheel 1. Said pawl 5 is adapted to slide in said socket in arm 6, and a spring 9 is interposed between said pawl and the bottom of said socket to normally hold it into engagement with the rim of said wheel 1. An angle-slot 10 is formed in one side of said arm, and a transversely-projecting pin 11, mounted in one side of pawl 5, projects therein. By this means the pawl is held square with its work, and when it is desired to hold said pawl out of engagement with the rim of said wheel it may be forced downwardly in said socket and turned so that pin 11 will pass beyond the vertical portion of said slot 10 into its horizontal portion, as will be readily understood. Pivoted to the horizontal arm of said bell-crank lever 6 is a weighted rod 12, having a screw 13 mounted in its lower end, which is adapted to engage with the horizontal plate 14. Said horizontal plate 14 extends transversely of the carriage and is mounted on a stem 15, which extends down through a suitable verti-

cal bearing in said carriage and is provided with a roller 16, eccentrically journaled on its lower end, which is formed with tapered sides adapted to travel in a groove 17 in the top of the bed A beneath said groove, provided with corresponding tapered sides, whereby sufficient friction is secured to rotate said roller and reciprocate said stem 15 and plate 14 at the end of the travel of the carriage and 10 through the connection 12 and the bell-crank lever 6 operate pawl 5 to feed wheel 1 forward one or more teeth. The length of the movement of said pawl 5 is regulated by the adjustment of the screw 13 in the lower end 15 of weight 12 and by the adjustment of a set-screw 19, mounted in a suitable bearing 20 behind the vertical arm of said lever and adapted to serve as a stop to limit the backward motion thereof, its position being secured by a jam-nut 21. By this means, as will be readily seen, the travel of the pawl 5 may be regulated as desired, so as to feed wheel 1 forward one, two, or more notches at each movement of the lever.

25 The rim 22 is mounted in a circumferential recess in one side of wheel 1 with its periphery flush with the points of the teeth and is adapted to turn thereon. A cam or trip 23 is set in one side of the periphery of said rim 30 to project slightly therefrom. A transversely-extending pin 24 is mounted on one side of pawl 5 and extends across the path of said cam, which when brought to a position to reach the same will thus throw said pawl out 35 of engagement with the wheel 1. A lever 25 is mounted on a pivot 26 on the side of said rim 22 and has a pawl 27 extending over the periphery of wheel 1 and adapted to engage with the teeth thereon. A spring 28 is connected with a projection on said lever at one 40 end and at the other end to pin 29 on said rim at a point beyond. A thumb piece or lug 30 is formed on said rim adjacent to said lever. By pressing said lever 25 toward said thumb-piece 30 the pawl 27 will engage with the teeth of said wheel 1 and operate to force said rim back on said wheel to draw the trip 23 away from the position where it will contact with pin 24 in the side of pawl 5. Thus when the 45 wheel 1 has been fed by the mechanism just described to the point for which it has been set and the trip 23 has reached a position where it will throw pawl 5 out of engagement if the work has not been ground to the size desired by reason of the wear of the grinding-wheel said trip is drawn back to permit the feeding operation to continue until the work is reduced to the size desired.

To this point the construction and operation of the mechanism is substantially the same as that shown in my aforementioned patent, No 640,669. In order that the operation may continue until the work has been ground to the exact size without any care or 60 attention from the operator, I have provided

a micrometer-gage 40, mounted on the outer end of a sleeve 41, having a rack-bar upon its inner end, which sleeve is mounted to slide in a horizontal bearing formed in one side of casing 42, which is mounted in a suitable support C² on the top of table C. A rod 43 is adjustably secured to the barrel of said gage by a set-screw s and its outer end adapted to rest against the work w, it being adjustably mounted to provide for different sizes of work. 70 A pinion 44 is mounted upon a transverse shaft 45 in said casing and engages with the rack-bar on said sleeve 41. An arm 46, also mounted on shaft 45, has a segment-gear 47 on its opposite end, which engages with a pinion 48 in the rear of said casing. An arm 50 is mounted on said shaft 49 and extends forward and has a contact-head 51 on its forward end. A contact-spring 52 is mounted upon a bolt 53, which projects through the 80 side of the casing and is electrically connected to one wire 54 of the electric circuit. Said spring extends down to the lower side of the casing and at its lower end is formed curved and arranged with its face in position to be 85 contacted by the head 51 of the arm 50 when it reaches this position. A sliding bar 55 is mounted in one side of standard C² and has a bracket 56 on its outer end containing a perforation through which projects the outer end 90 of rod 43, which thus serves to hold said rod steady and prevent it from vibrating under contact with the work, as will be seen. The weight of arm 50 and its head 51, operating through the connecting-gear, serves to feed said rod 100 43 forward as the size of the work is reduced, keeping the end of said rod in close contact therewith. As the rod travels forward the head 51 of arm 50 will gradually pass from the position shown in whole lines in Fig. 5 105 until it contacts with the spring 52 near its lower end and moves on until it breaks contact therewith by passing beyond said lower end when it reaches the position shown in dotted lines, which will be when the work 110 has reached the predetermined size.

A pair of electric magnets M and M' are mounted on a suitable part of bracket 8 adjacent to the rim of wheel 1, being secured together by frame-pieces m and m', as shown. 115 A plunger 60, having an antifriction-roller 61 upon its lower end in position to engage with a projecting arm 59 on lever 25, is mounted in bearings in said frame-pieces m and m' between said magnets M and M' and has an armature 62 secured to its outer end adjacent to and within the field of said magnets. A cell-battery B' and B² is mounted within the bed A on a bracket a, as shown. The wire 120 54 runs to said cell B', which is coupled to cell B², and wire 57 runs from said cell B² to magnet M'. The apertures in the frame through which said wires pass are lined with insulating material, as shown. A piece of insulating material 63, having a metal bar or 125 130

staple 64 in its outer edge, is secured on one side of rim 22. Metallic arms 65 and 66 are secured on each side of a lug 67, of insulating material, mounted on the end of arm 68, secured to bracket 8 and projecting to a point adjacent to said contact 64 when in the position shown in Fig. 3. A wire 69 electrically connects arm 65 with magnet M. Arm 66 has its lower end 70 bent backward in a position where it will be contacted by the vertical arm of bell-crank lever 6 upon each of its forward motions. It will thus be seen that while said bell-crank lever 6 is momentarily in contact with point 70 of arm 66 and said arms 65 and 66 are in contact with bar 64, as shown in Fig. 3, a complete circuit through magnets M is established, which energizes said magnets and draws the armature 62 in contact with their poles, which operates plunger 60 to press roller 61 against the projecting arm 59 of lever 25 and operates said lever to recede the rim 22 one notch in the same manner as when said lever is operated by hand against the projecting lug 30.

The operation of the invention is as follows: The grinding operation is begun and continued in the usual manner as shown and described in my former patents above referred to, and the automatic feed mechanism works mechanically, as described, until the wheel 1 has been revolved to bring the trip 23 into the position shown in Fig. 3, when it strikes the pin 24 in the side of pawl 5 and would thus hold said pawl out of engagement with the teeth in the periphery of wheel 1 and prevent the further operation of grinding. At this point, however, the contact-bar 64 connects the arms 65 and 66, and if the work has not reached the size required the head 51 of arm 50 is still in contact with spring 52, thus completing an electric circuit through the wire 54, batteries B' and B'', wire 57, magnets M and M', wire 69, arm 65, contact-bar 64, arm 66, and through the machine back to the battery, when lever 6 is thrown forward against the contact-point 70 in said arm 66. Thus at each motion of said lever 6 said circuit will be closed, the magnets energized, and through the mechanism above described rim 22 will be drawn back one notch and trip 23 drawn out of engagement with the pawl, so that the pawl will continue to operate to feed wheel 1, and through it the work, so long as arm 50 and spring 52 are in contact. As soon as the work has reached the predetermined size for which said micrometer-measure is set said head 51 of arm 50 will pass over the end of spring 52, the electric circuit will be broken, and the trip 23 will then hold pawl 5 out of engagement with the periphery of said wheel and the operation of grinding will stop.

While I have described this invention as applied to a grinding-machine, it will be understood, of course, that it may be applied to any work-reducing machine for which it is adapted.

Having thus fully described my said invention, what I claim as new, and desire to secure by Letters Patent, is—

1. An automatic sizing mechanism for grinding-machines comprising a feed-wheel having ratchet-teeth in its periphery, a rim mounted on said wheel having a pawl-lever adapted to engage with said teeth, a cam or trip mounted in the periphery of said rim to engage the operating device and throw it out of operation, and an electrically-operated plunger arranged to engage said pawl-lever and operate it to turn back said rim and cam out of engagement with said operating device until the work has reached a predetermined size, substantially as set forth. 70

2. In a grinding-machine, an indicator for automatically determining the size of the work comprising a rod engaging with said work and adjustably connected to a micrometer, 85 said micrometer being connected to mechanism which will break an electric circuit at the point where the work has reached the predetermined size and stop the operation of the grinding automatically, substantially as set forth. 90

3. In a grinding-wheel the combination with the mechanism for automatically feeding the grinding-wheel to the work, of an electric device for receding the stop-ring on the feed-wheel, a micrometer to determine the size of the work, electrical connections between said micrometer and said automatic feeding device, and mechanism connected with said micrometer which breaks the electric circuit 100 when the work has reached the size desired, substantially as set forth. 100

4. In a grinding-wheel, the combination of a ratchet feed-wheel for the feeding mechanism of the grinding-wheel, a rim mounted thereon having a cam for disengaging the main operating-pawl, a lever mounted on said rim for receding said cam from engagement with said main operating-pawl, electric magnets adjacent to said wheel, a plunger operated by the armature thereof adapted to contact with said pawl-lever, an electric circuit connecting said magnets with the micrometer-gage, and mechanism connected with said micrometer-gage for breaking the circuit when 110 the work has reached the predetermined size, substantially as set forth. 115

5. An automatic sizing device for grinding-machines comprising a ratchet feed-wheel for operating the grinding-wheel mechanism, a main operating-pawl engaging therewith and operated by the travel of the carriage, a rim adjustably mounted upon said wheel carrying a cam for throwing said main pawl out of engagement when brought in contact therewith, a pawl-lever for adjusting said rim upon said wheel, an electric magnet mounted alongside of said wheel and having a plunger connected with its armature in position to contact with and operate said lever, the electric 125 130

- 5 circuit being arranged to be closed by the forward movement of said operating-pawl, a micrometer for determining the size of the work electrically connected in said circuit, 5 and a circuit-breaking mechanism connected with said micrometer to break said circuit when the size of the work for which it is set has been reached, substantially as set forth.
6. In an automatic sizing device for grinding-machines, an electric circuit connecting the work-size indicator and the motor for receding the stop-feed ring, having a plurality of circuit-closers by which the farther advance of the reducing device is continued after the normal feeding for which it has been set has been reached, and a circuit-breaking device controlled by said indicator, by which said farther advance is arrested, substantially as set forth.
7. In an automatic sizing device for grinding-machines, a ratchet feed-wheel having a rim mounted thereon, a cam on said rim for throwing the driving-pawl out of engagement, a pawl-lever mounted on said rim for adjusting the same upon said wheel, and an electric motor for actuating said lever connected in an electric circuit for energizing said motor and controlled by the work-size indicator, substantially as set forth.
8. In a grinding-machine, the combination of the automatic feeding mechanism for the grinding-wheel comprising a ratchet-wheel for operating the same, a main pawl engaging with said ratchet-wheel for operating the same, means for operating said pawl at each reversal of the motion of the carriage, an adjustable rim mounted on said wheel and carrying a cam for throwing the main pawl out of engagement at a predetermined point, a lever for operating said rim upon said wheel, a circuit-closing contact-bar also carried by said rim, electric magnets for operating a plunger for actuating said lever, contact-arms insulated from each other and mounted in position to contact with the contact-bar carried by said rim, one of said arms being connected with one of said magnets, the other of said magnets being connected with the contact-point connected with the work-size indicator and the other of said arms being located adjacent to the main operating-pawl and in position to be contacted thereby to close the circuit at each motion of the pawl, substantially as set forth.
9. In a grinding-machine the combination of the slidably-adjustable rod secured in the micrometer-barrel and adapted to engage the work, said barrel being connected by a screw-thread with a sleeve having a rack-bar thereon, a lever mounted on a spindle geared to said rack-bar and connected by a gear to another spindle bearing an arm adapted to engage with a contact-point while the grinding is progressing and pass from engagement therewith when the size of the work desired

has been reached, and a feeding mechanism for the grinding-wheel electrically connected in the same circuit, whereby the feeding of the grinding-wheel to the work is regulated, substantially as set forth.

7c

10. In a machine for reducing work, the combination with the mechanism for feeding the reducing-tool to said work, of a ratchet feed-wheel for operating said mechanism, a pawl operated by the travel of the carriage for operating said feed-wheel, a rim adjustably mounted on said feed-wheel provided with a cam to disengage the operating-pawl at a predetermined point electrically-operated mechanism for receding said rim when it has reached said point controlled by the work-size indicator, said parts being electrically connected, and mechanism arranged to break the circuit when the work has reached the predetermined size whereby said cam will then hold the operating-pawl out of engagement with said feed-wheel, substantially as set forth.

75

80

11. In a grinding-machine, the combination of the mechanism for feeding the grinding-wheel to the work, a feed-wheel for operating said mechanism provided with ratchet-teeth in its periphery, a reciprocating pawl operated by the travel of the carriage for actuating said feed-wheel, a rim adjustably mounted on said feed-wheel and provided with a cam arranged to disengage said operating-pawl when the wheel has been fed to bring said cam into engagement therewith, a device for receding said rim upon said wheel, electrically-operated mechanism for actuating said device, an intermittent circuit closer and breaker controlled by the operating-pawl, and a permanent circuit-breaker controlled by the size-indicator (which is connected in the same electric circuit) when the work has reached the predetermined size, substantially as set forth.

90

95

100

105

12. In a grinding-machine, the combination of the feeding mechanism for feeding the grinding-wheel to the work, a ratchet feed-wheel for operating the same, a pawl mounted to be actuated by the travel of the carriage for operating said feed-wheel, an arm adjustably mounted on said wheel having a cam for throwing said pawl out of engagement with said feed-wheel, a pawl-lever pivoted thereto for moving said rim step by step, an electric magnet mounted alongside of said wheel and having a plunger connected with its armature and arranged to operate said lever when said magnet is energized, terminals of the two branches of the circuit arranged in proximity to said wheel, a contact-bar in the periphery of said ring arranged to connect said terminals when the cam reaches the point where it will contact with the operating-pawl, one of said terminals having its opposite end in position to be contacted by the pawl upon its forward motions whereby the circuit is closed by each forward motion of said pawl, and broken by its receding motion, a work-size

110

115

120

125

130

indicator electrically connected in the same circuit embodying mechanism which breaks said circuit when the work reaches the predetermined size, substantially as set forth.

5 13. In a grinding-machine, the combination of the mechanism for feeding the grinding-wheel to the work, a ratchet-wheel for operating said mechanism, a pawl for operating said ratchet-wheel, a trip for throwing said pawl 10 out of operation at a predetermined point, an electrically-operated device for receding said trip to allow said pawl to continue to advance said wheel, a work-size indicator connected in the same electric circuit and embodying mechanism 15 arranged to break said circuit when the work reaches the predetermined size, substantially as set forth.

14. In a grinding-machine, the combination of a work-size indicator comprising a sliding rod arranged to be held against the work, gearing connecting said rod with a traveling contact point or head, a second contact-point of a length to allow for the travel of said first contact-point in contact therewith until the 25 work has reached the predetermined size when it will pass therefrom and break the contact, an electric circuit connected with said second contact-point on the grinding-wheel feed mechanism, mechanism for automatically operating the same, an electric device for continuing said mechanism in operation until the work has been reduced to the predetermined size, said mechanism being controlled by said work-size indicator, substantially as set forth.

35 15. An automatic sizing device comprising an indicator bearing upon the work, a device for prolonging the feed of the reducing-tool until the predetermined size of the work has been reached, an electric motor for operating 40 said device, an electric circuit connecting said indicator and motor embodying a plurality of circuit-closing points, whereby the feed is continued intermittently until the predetermined size of the work has been reached and then permanently stopped, substantially as set forth.

45 16. In an automatic sizing device for grinding-machines, the combination of the indicator arranged to be adjusted to various sizes of work, an extensible rod bearing against said 50 work and an extensible bar bearing a support for said rod close to said work, substantially as set forth.

17. In an automatic sizing device, a feed mechanism operated by the power of the machine and stopped mechanically, a feed-pro-

longing mechanism operated by an electromagnet, by which the mechanical or power feed is made to proceed until the electric circuit is broken, an electric circuit having a plurality of circuit-breaking points by which the 60 circuit at any time is only momentarily closed, and a size-controlling device which finally breaks the circuit when the predetermined size has been reached, substantially as set forth.

18. In an automatic sizing device, a feed 65 mechanism operated by the power of the machine and stopped mechanically, a feed-prolonging mechanism operated by an electromagnet by which the power-feed is made to proceed until the electric circuit is broken, a 70 size-controlling device by which the electric circuit is broken when the predetermined size of the work has been reached, said circuit having three points of opening and closing by which the circuit is only momentarily closed 75 at any time and only one when nearing the predetermined size of the work, substantially as set forth.

19. In an automatic sizing mechanism for grinding-machines, a ratchet feed-wheel having a receding pawl, disengaging mechanism, an electromagnet for receding said disengaging mechanism, said electromagnet being connected in a circuit with a device controlled by the size of the work to break the circuit when 85 the predetermined size of said work has been reached, substantially as set forth.

20. In an automatic sizing mechanism, an automatic feeding mechanism operated mechanically by power from the machine, an automatic stop to stop the feed by mechanical action, and an electrically-controlled feed-stop receding device, substantially as set forth.

21. In an automatic sizing device, an automatic feed mechanism operated mechanically 95 and stopped mechanically, a feed-extending device operated by an electromagnet, by which the mechanical power-feed is allowed to proceed until the electric circuit is broken by a size-controlling device when the predetermined size has been reached, substantially as set forth.

In witness whereof I have hereunto set my hand and seal, at Waynesboro, Pennsylvania, this 14th day of March, A. D. 1904.
